TALKING-MACHINE.

1,293,489.

Specification of Letters Patent.

Patented Feb. 4, 1919.

Application filed July 2, 1915. Serial No. 37,731.

To all whom it may concern:

Be it known that we, MERWIN E. LYLE,
JOHN J. SCULLY, and FRANK L. CAPPS, citizens
of the United States of America, and
residents of Bridgeport, Connecticut, have
invented a new and useful Improvement in
Talking-Machines, which invention is fully
set forth in the following specification.

This invention relates to talking machines,
and has for its object to produce a machine
of this character at a minimum cost without
decreasing its efficiency or detracting from
the character of the sound reproductions se-
cured therefrom. The invention has refer-
ence more particularly to the disk form of
talking machines, either of the so-called
"hornless" or the horn type, and provides
an extremely cheap cabinet or casing for the
motor mechanism and support for the tone-
arm and parts connected therewith. These
ends are accomplished by providing a base
and top, shown as struck up from sheet ma-
terial such as sheet-metal, and side walls
composed of sheet material such as sheet-
metal retained between the base and top by
suitable means such as bolts, the motor pref-
erably being hung from the top of the cas-
ing by suitable supporting bolts. In the
case of the "hornless" form of machine, the
wall of the cabinet is so shaped as to cause
it to form the sound amplifier into the nar-
row or reduced end of which the tone-arm
enters; whereas, in the horn form of ma-
chine, the tone-arm and horn are suitably sup-
ported on the outside of the casing. In the
form shown, for universal movement in a
bracket at the side of the machine on a bent
rod or wire support, the tone-arm and horn
being so mounted upon the said rod as to
be capable of movement in a vertical direc-
tion, and said rod itself being free to move
in a horizontal direction in the bracket,
while the bent rod at the same time forms
an efficient support for the tone-arm proper
when the reproducer is thrown to one side
and is not resting upon the record.

The inventive idea is capable of receiving
a variety of mechanical expressions, some of
which, for the purpose of illustrating the
invention, are shown on the accompanying
drawings, but it is to be expressly under-
stood that such drawings are for the pur-
pose of illustration only, and not for the
purpose of defining the limits of the inven-

tion, reference being had to the appended 55
claims for that purpose.

In said drawings:

Figure 1 is a perspective view of the
"hornless" form of the invention;

Fig. 2 is a perspective view of the base, 60
the walls and the top supporting the tone-
arm and motor, the parts being separated
in vertical alinement to better disclose the
construction;

Fig. 3 is a vertical sectional view of the 65
tone-arm support;

Fig. 4 is a side elevation, with parts
broken away, of the horn form of the ma-
chine; and

Fig. 5 is a perspective view of the bracket 70
and rod or wire for mounting the tone arm
and horn.

Referring to the drawings, in which like
reference numerals designate corresponding
parts throughout the several views, and first 75
to Fig. 2, 1 is a base shown as struck up from
a single piece of sheet material such as sheet-
metal and having holes or openings 2, 2
formed therein. 3 is a top plate also shown
as struck up from similar material and hav- 80
ing openings 2', 2' formed therein in verti-
cal alinement with the openings 2 in the
base plate 1. This top plate 3 has an open-
ing formed in one corner thereof, over
which opening is mounted a tone-arm sup- 85
port 4. In that portion of the top plate 3
diagonally across from the tone-arm sup-
port 4 is formed an opening 5 through which
the upwardly extending driving shaft 6 for
the turn-table projects, which shaft is driven 90
by a suitable motor 7 shown as supported
by bolts 8, 8 extending through the top
plate 3.

The walls 9 of the cabinet are formed of
a single piece of sheet material such as sheet- 95
metal bent to form as shown in Fig. 2, one
end, as 10, being shown as bent to form a
tubular opening in alinement with two of
the openings 2, 2' in the top and bottom, and
the sides 11, 11' and 11'' being bent at ap- 100
proximately right angles to each other.
though preferably with the angular por-
tions rounded, as shown, in order to pro-
duce neatness of finish. This produces three
sides of the cabinet. From the side 11'', the 105
sheet material is bent preferably on an arc
11³ and its end 12 brought into contact with
the side 11' near the point where said wall

joins the side 11, said end 12 being preferably connected to the side 11' in any suitable way, as by soldering.

Depending from the under side of the top portion 3 in the form illustrated and registering on the under side with the tone-arm support 4 is an elbow 13, which elbow preferably flares outwardly at its lower horizontal end, as shown. The parts being thus provided, the bent wall portion of the cabinet is placed upon the base portion 1, preferably just within a marginal flange 14 struck up on said portion, and the top portion 3 with its supported parts is then placed upon the wall portion, said top portion 3 being preferably provided with a downwardly extending peripheral flange 15 which extends over and embraces the wall portion. When thus assembled, the motor occupies the confined space between the wall portions 11', 11'' and 11'', and the elbow 13 rests within the space between the wall 11 and the arc portion 11'', which wall portion 11 and arc portion 11'', together with the bottom and top, constitute the inclosed sound amplifier or horn of the machine.

With the parts in this position, suitable bolts 16 are then passed through the corresponding openings 2, 2' in the bottom and top, and the whole secured together by nuts 16', Fig. 1, on said bolts.

An opening 17 is provided through the wall 11'' for the winding shaft for the motor, and an opening 18 is also provided in said wall for the start-and-stop and speed-regulating device for the motor.

The tone-arm support 4 is provided with two oppositely disposed horizontal slots 19, within which rest the ends of a horizontal pin 20 passing through the spherical enlargement 21 on the tone-arm 22, which enlargement fits closely within the upper portion of the support 4 but so as to permit the tone-arm to turn freely therein about vertical and horizontal axes. This construction enables the tone-arm to have universal movement upon its bearing without providing any opening flaring outwardly from the interior of the sound conduit.

Within the tone-arm support 4 and beneath the spherical enlargement 21 of the tone-arm is mounted a stirrup 23, which stirrup is connected to the wall of the tone-arm support on one side, as 24, at a point higher up, that is in a higher horizontal plane, than is the other side 25 of the stirrup, and a coiled spring 26 is connected at its lower end to the bottom of said stirrup and at its upper end to the pin 20.

The higher end 24 of said stirrup is in a position to be engaged by the lower edge of the spherical portion of the tone-arm when the latter is swung to one side of the record and the sound-box end thereof released, and thereby limiting the downward tilting or

rocking action of the tone-arm and acting as a support or stop to hold the tone-arm in approximately horizontal position. On the other hand, the lower portion 25 of the stirrup is in a position where it will not be engaged by the lower edge of the spherical portion of the tone-arm when the tone-arm is considerably elevated. At the same time the point where the spring 26 is connected to the stirrup is sufficiently removed from the point where said spring is connected to the pin 20 to afford the necessary yielding action and yet enable the spring to hold the parts in normal position and prevent play or rattle between the parts. By this means a single piece of bent wire is caused to operate not only as a tone-arm stop but also as an abutment for the spring 26.

The usual or any suitable turn-table 27 is mounted on the vertical drive shaft 6, which table supports the usual or any suitable record 28 in position to be engaged by the stylus of the reproducer 29.

Referring to Figs. 4 and 5 showing the horn form of the machine, a suitable base 31 and top 33, which may be made of sheet-material, such as sheet-metal, are struck up and vertical walls 34, preferably consisting of a single piece or strip of sheet material such as sheet-metal bent into approximately rectangular form are provided and the whole united together by bolts 35, as will be readily understood from an inspection of Fig. 4, the motor being supported from the top portion 33 by depending bolts 100 or otherwise. Projecting outwardly from one of the side walls 34 is a bracket 36 which is preferably constructed of sheet-metal bent into suitable form and bolted or riveted to said wall 34, which bracket has preferably an upper portion 36' and a lower base portion 36'', as shown, and near the outer extremity of the two portions 36', 36'' are formed two openings 37, 37 in vertical alignment. A rod or stiff wire 38 is bent into the form shown in Figs. 4 and 5, that is, with an upwardly extending vertical portion *a*, an inwardly extending approximately horizontal portion *b*, a second horizontal portion *c* extending approximately at right angles to the first horizontal portion *b*, and a third horizontal portion *d* bent on a reverse curve and extending above and approximately parallel with the second horizontal portion *c*. The horn and tone-arm are preferably formed as a unit (though not necessarily integral), gradually expanding from the reproducer 39 to the outwardly flared portion 40 of the horn, the whole preferably being formed on a reverse curve so that the horn or flared portion 40 extends out over the reproducer. The horizontally extending portion *d* of the supporting rod 38 preferably extends directly through the walls of the tone-arm adjacent

to said reverse curve and is retained in position by an expanding pin 41 passing through an opening in the portion d , preferably with a washer 42 placed between 5 said expanding pin and the wall of the tone-arm.

As thus constructed, the reproducer, tone-arm and horn are free to move in a horizontal direction, turning upon the portion 10 a of the rod 38 as an axis; the tone-arm and horn with its attached reproducer are free to move in a vertical direction, turning upon the horizontal portion d of the rod 38 as an axis; and the horizontal portion c 15 forms a support for the tone-arm when the reproducer is not resting upon the record. Of course, it will be understood that a suitable lug or abutment α is formed on the vertical portion a of the rod 38 to provide 20 a shoulder to limit the downward movement of the portion a through upper opening 37 in the bracket 36.

It will be observed that the invention thus 25 provides an extremely simple and cheaply manufactured cabinet, either for the horn or "hornless" form of machine, made of sheet material which can be struck up at a minimum cost (and which may be enameled or colored as desired); that the mounting for 30 the tone-arm, whether in the horn or "hornless" form of machine, is extremely simple and yet provides efficiently for all of the movements incident to the perfect operation of said tone-arm; and that all of the 35 parts are capable of being manufactured without the employment of skilled labor.

Various changes and modifications may 40 be employed without departing from the spirit of the invention as defined in the appended claims. It will be apparent to those skilled in the art that all such changes and modifications are designed to be covered by said claims.

What is claimed is:

45 1. In a talking machine, the combination of a casing composed of a flanged top of sheet material, a flanged base of sheet material and side walls of sheet material held between said top and base and in engagement with said flanges, and sound-reproducing instrumentalities supported by said casing.

50 2. In a talking machine, the combination of a casing composed of a flanged top of sheet material, a flanged base of sheet material and side walls of sheet material held between said top and base and within and in engagement with said flanges, bolts passing through the top and base and clamping 55 the side walls therebetween, and sound-reproducing instrumentalities supported by said casing.

60 3. A talking machine casing composed of a top and base of sheet material and side 65 walls of sheet material held between said

top and base, one of said side walls being bent inward to form one of the sides of an inclosed flaring horn.

4. A talking machine casing composed of a top and base, and side walls comprising a 70 single sheet of material bent around three sides of a rectangle and held between said top and base, said sheet at one end being bent inward to form with a side wall a sound-amplifying compartment.

75 5. A talking machine casing composed of a top and base, and side walls comprising a single sheet of material bent around three sides of a rectangle and held between said top and base, said sheet at one end being 80 bent inward and joined to the middle of said side walls to divide the interior of said casing into sound-amplifying and motor-in-closing compartments.

85 6. A talking machine casing or cabinet composed of a top and bottom of sheet material and side walls of sheet material held between said top and bottom, the sheet constituting the side walls being bent around three sides of a rectangle and then bent in- 90 ward and its end joined to one of the side walls, whereby there is formed an inclosed space for the motor mechanism and an out- 95 wardly flaring horn space open at one end, substantially as described.

95 7. A talking machine casing or cabinet composed of a substantially rectangular top of sheet material having a tone-arm opening formed in one corner portion and a drive- 100 shaft opening diagonally opposite said tone-arm opening, a base of sheet material, and side walls of sheet material, the sheet constituting the side walls being bent around three sides of a rectangle and having its end portion bent inward and joined to the middle one of said three sides, whereby there is formed an outwardly flaring sound-amplifying space open at one end and with its closed end communicating with said tone-arm opening in the top, substantially as de- 105 scribed.

110 8. A talking machine casing or cabinet having a substantially rectangular top of sheet material with a tone-arm opening formed in one corner portion, a tone-arm support over and surrounding said opening, a base of sheet material, and side walls of sheet material, the sheet constituting said side walls being bent around three sides of a rectangle and having its end portion bent 115 inward and joined to one of said three sides, whereby an inclosed horn is formed communicating with said tone-arm opening at its closed end.

120 9. In a talking machine, the combination of a casing composed of a top and base and a single sheet of material bent to constitute the sides of said casing and held between said top and base, one end of said sheet of material being bent inward and dividing the 110

4
interior of said casing into a sound-amplifying and a motor-inclosing compartment, a motor suspended from said top within said last-named compartment, a record support without said casing driven by said motor, and sound-reproducing instrumentalities supported by said casing in operative relation to said record support.

10. A talking machine casing having its side walls constructed of a single sheet of material bent to shape, a portion of said sheet being bent inward to constitute a wall

of a sound-amplifying compartment in said casing.

In testimony whereof we have signed this 15 specification in the presence of two subscribing witnesses.
